L. G. MILLER,
COMBINED STIFFENER AND CAR DOOR HINGE,
APPLICATION FILED FEB. 18, 1921.

1,377,717.

Patented May 10, 1921.

Inventor
Louis G. Miller:

GEO. E. THACKRAY
Attorney

UNITED STATES PATENT OFFICE.

LOUIS G. MILLER, OF WESTMONT BOROUGH, PENNSYLVANIA.

COMBINED STIFFENER AND CAR-DOOR HINGE.

1,377,717.

Specification of Letters Patent. Patented May 10, 1921.

Application filed February 18, 1921. Serial No. 446,060.

To all whom it may concern:

Be it known that I, LOUIS G. MILLER, a citizen of the United States, and a resident of the borough of Westmont, in the county 5 of Cambria and State of Pennsylvania, (whose post-office address is Johnstown, Pennsylvania,) have invented certain new and useful Improvements in Combined Stiffeners and Car-Door Hinges; and I do hereby 10 declare the following to be a full, clear, and exact description of the invention, such as will enable others skilled in the art to which it appertains to make and use the same.

15 My invention relates to the construction of cars and particularly of metal cars, and consists generally of a construction whereby the car floor or the car hopper adjacent to the discharge doors is strengthened and reinforced by a metal member secured to or near the edge, and which in addition to serving as a strengthening member is also so constructed that it serves as a portion of the hinge on which the door operates. By combining these two features, I make a construction which is lighter, cheaper and more efficient than if these were separate items, as the weight and labor involved in my construction is less while its strength and usefulness is maintained.

20 Another object of my invention is that the combined reinforcing and hinge member may be made integral in all respects from a steel or malleable iron casting and the hinge 25 pintle portion is also integral and obviates the use of supplementary pins, nuts, washers and cotter pins which are customarily used in this connection. The use of my combined member will minimize the amount and cost 30 of stiffening and strengthening a car floor or the hopper sheets thereof adjacent to the door opening, thereby providing the required rigidity without the use of unnecessary parts, and my construction is also simple, economical and efficient.

35 Referring now to the annexed sheet of drawings which forms a part of this specification:—Figure 1 is a vertical longitudinal sectional elevation through the hopper and 40 doors of a portion of a car taken on the line I—I of Fig. 2. Fig. 2 is a vertical transverse sectional elevation taken on the line II—II of Fig. 1. Fig. 3 is an enlarged detail 45 sectional elevation of a portion of a car hopper and door taken on the line I—I of Fig.

2. Fig. 4 is a plan view of one of the stiffener and hinge members, Fig. 5 is a front elevation of the same, and Fig. 6 is an end elevation thereof.

50 Referring now to the characters of reference on the drawings:—1 indicates a portion of a car in general, 2 are the side hopper sheets thereof, 3 is the center ridge plate of the car which covers the center sills as illustrated, 4 and 5 are the transverse hopper sheets, 6 is my combined stiffener and door hinge member in general, 7 is the downwardly depending flange portion thereof, the lower portion of which is curved as illustrated in order to provide for the bending 55 movements to which it is subjected, the most metal being at the center and tapering thence toward the ends where less metal is needed to meet the bending stresses, 8 are transverse ribs formed integral with the rest of the bar 60 between which ribs is an integral member 9 of circular cylindrical section adapted to form the pintle of a hinge, 10 are triangular longitudinal ribs adapted to reinforce the structure, 11 are rearwardly or outwardly projecting 65 flat portions adapted to be secured to the car floor or car hopper bottom near the edge thereof and adjacent to the door opening, these providing a greater width in a lateral direction in order to insure strength and stability to the construction in general, 12 are bolt or rivet holes provided in the upper member of the main portion of the stiffener 70 bar, and 13 are bolt or rivet holes in the rearwardly projecting portions 11, these being 75 also adapted for securing the same in position. A space or opening 14 is provided above the hinge pintle member 9 adapted to allow the insertion of the end of the hinge strap therethrough, which hinge strap partially surrounds the member 9. The car door which is shown as of pressed steel form, is 15, and is provided with a hinge strap 16 which may preferably be secured to the under side 80 thereof and projects downwardly therefrom 85 through the opening 17. The hinge strap is provided with a bent portion 18 and is bent in a semi-circular form in order to partially surround the hinge pintle 9 as illustrated, 90 while at the same time permitting its introduction into position. Between the end of the car door and the end 18 of the hinge strap I insert a hinge or filler block 19 which is adapted to fill the space therein, the upper 95 end also conforming to the curvature of the 100

105

110

hinge pin 9, and this filler may be either bolted or riveted, although I have illustrated it as secured by the rivet 20.

Although I have illustrated my invention 5 in connection with a certain type of hopper car known as the H-25, I wish it understood that it can be used in connection with any type of car which is provided with door openings and doors.

10 Although I have described and illustrated my invention in considerable detail, I do not wish to be limited to the exact and specific details thereof, as shown and described, but may use such modifications in, substitutions 15 for, or equivalents thereof, as are embraced within the scope of my invention, or as pointed out in the claims.

Having thus described my invention, what I claim and desire to secure by Letters Patent is:—

1. A car stiffener having a portion adapted 20 to be secured to the car adjacent the door opening thereof and provided with integral strengthening flanges projecting outwardly 25 therefrom and one or more hinge pintle portions, integral with said stiffener.

2. An integral stiffener and car hinge member comprising a portion adapted to be secured to and against the car floor and 30 having flanges or ribs extending outwardly from same and a plurality of substantially cylindrical pintles adapted to rotatably support a door hinge.

3. An integral stiffener and door hinge 35 member comprising a flat portion adapted to be secured to a car floor and provided with one or more longitudinal flanges projecting downwardly therefrom and a plurality of pairs of transverse ribs between each 40 pair of which is a substantially cylindrical pintle, adapted to receive the car door hinge.

4. An integral stiffener and door hinge 45 member comprising a flat portion with a pair or smaller flat portions projecting substantially parallel to and outwardly there-

from, all of said flat portions being adapted to be secured adjacent to a car floor, a longitudinal stiffening flange projecting downwardly therefrom, deeper at its center than at its end portions, a plurality of pairs 50 of transverse ribs projecting downwardly from the longitudinally extending flat portion, between each pair of which is a substantially circular cylindrical pintle, adapted to rotatably support a car door hinge. 55

5. An integral stiffener and hinge member provided with a flat portion secured to a car floor near the door opening thereof and provided with a longitudinally and downwardly extending strengthening flange and 60 with a plurality of substantially cylindrical pintles spaced apart from the flat portion and adapted to rotatably support the door hinge.

6. An integral stiffener and hinge member 65 provided with a flat portion secured to a car floor near the door opening thereof and provided with a longitudinally and downwardly extending strengthening flange and with a plurality of pairs of transverse ribs, 70 between each of which pairs is a substantially cylindrical pintle spaced apart from the flat portion and adapted to rotatably support a door hinge.

7. In a car, an integral stiffener and hinge 75 member provided with a flat portion secured to a car floor near the door opening thereof, said member having a longitudinally and an outwardly extending strengthening flange deeper at its center than at its 80 end portions, a plurality of substantially cylindrical pintles spaced apart from the flat portion and supported by transverse ribs connecting with the flat portion aforesaid, and car door hinges rotatably supported by said pintles. 85

In witness whereof I hereunto affix my signature.

LOUIS G. MILLER.
